UNITED STATES PATENT OFFICE.

WALTER S. ADAMS, OF PHILADELPHIA, PENNSYLVANIA, ASSIGNOR TO
JOHN A. BRILL, OF PHILADELPHIA, PENNSYLVANIA.

CAR-TRUCK.

SPECIFICATION forming part of Letters Patent No. 739,771, dated September 22, 1903.

Application filed June 21, 1902. Serial No. 112,588. (No model.)

To all whom it may concern:

Be it known that I, WALTER S. ADAMS, a citizen of the United States, and a resident of the city and county of Philadelphia, State of Pennsylvania, (and whose post-office address is care of the J. G. Brill Co., in said city,) have invented certain new and useful Improvements in Car-Trucks, of which the following is a specification.

10 My invention has relation to pivotal car-trucks adapted to be employed in connection with electric motors, and it has more especial relationship to trucks wherein the bolster is supported upon longitudinally-disposed upwardly-arched semi-elliptic or leaf springs arranged at each side of the truck below the top bar of the side frames.

The object of my invention is to simplify and reduce the cost of construction and maintenance of trucks of this kind and at the same time preserve a great many of the features of trucks of this class—namely, better equalization of the load under varying conditions of service, to produce an easy-riding truck both with reference to the superposed car-body and the action of the truck on the track-rails, to enable the axles of the wheels to be brought comparatively close together to produce what is known as a “short-wheel-base truck,” and to secure many other desirable features hereinafter referred to.

My invention resides in the novel construction and combination of parts hereinafter described, and further pointed out in the claims.

35 In the drawings forming part of this specification, Figure 1 is a side elevation of a truck made in accordance with my improvements. Fig. 2 is a plan view of the same. Fig. 3 is a transverse sectional elevation on the line xx , Fig. 2. Fig. 4 is a side elevation showing the bolster in a modified form, and Fig. 4^a is a perspective view of the spring-plank hanger. Fig. 5 is a side elevation of a further modification; and Fig. 6 is a transverse section of 40 the same on the line 6 6, Fig. 5. Fig. 7 is a side elevation of a further modification, and Fig. 8 views of several of the parts employed therein. Fig. 9 is a side elevation of a further modification, and Fig. 10 is a plan view 45 of the link-hanger and spring-cap.

50 My invention is illustrated herein in con-

nection with an otherwise conventionally-constructed truck, which except for those features hereinafter more specifically described and claimed are not new with me.

55

Referring to Figs. 1, 2, and 3, 1 represents the axles; 2, the wheels; 3, the axle-boxes. The truck comprises the axle-box yokes or pedestals 4, having the inner and outer arms 5 6, extensions 7 from the outer arms connected transversely by cross-bars 8, the inner arms being connected by the top bars or chords 9, and between the tops of the axle-boxes 3 and the axle-box yokes extend the usual axle-box springs 10. From the inner 60 and lower end of the inner pedestal-arms are formed inwardly and longitudinally extending lugs 11, opening upwardly and having side flanges 12. These lugs may be connected together at their lower surfaces by the pedestal tie-bar or lower chord 13 of the truck-frame, and the arms 5 6 of the yokes may be connected by short bars 14 below the axle-boxes, thus tying the pedestals firmly together. At 15 are the transoms, formed of 65 angle-iron with their inner vertical faces 16 opposed to each other and their horizontal flanges 17 secured to inwardly-extending bracket-like webs 18, extending inwardly from the top bars 9. At 19 are the upwardly-arched semi-elliptic or leaf springs arranged longitudinally of the truck beneath or adjacent the top of the bars and having their ends 20 loosely supported upon the lugs 11 between the flanges 12, so as to permit them 70 to slide when being lengthened or shortened under pressure. In this form of truck the bolster 21, of any desired form and located between the transoms, is not supported directly upon and connected to the springs 19, 75 but is supported thereby and directly through the medium of additional bolster-springs 22, which latter are supported upon a spring-plank 23, which extends out under the top bar 9, the plank in turn being suspended 80 from the semi-elliptic springs by transversely-swinging links 24. In Fig. 1 are shown caps 25, seated upon the bonds 26 of the semi-elliptic springs and having recesses 27 at each side to receive the links 24, connected together by the headed cross-bars 28, upon 85 which rests a casting 29, which latter in turn

80

85

90

95

100

supports the spring-plank, to which it is fixed. The spring-plank supports the pair of short elliptic spring 22 (which may be transversely disposed, if desired) adjacent the links 24, 5 and upon these elliptic springs rests the bolster, and which may be provided with center and side bearings in the usual manner. A thrust-spring 30 may be employed, as shown, which extends between the top bar 9 of the 10 truck-frame and the ends of the bolster and which may be supported in place in the usual way. By this construction the bolster and spring-plank and the interposed bolster-springs may have the usual transverse or 15 lateral swing without involving the longitudinal semi-elliptic springs to any undesirable extent, if at all. While the latter are so supported they may be lengthened without involving strains upon themselves other than 20 the support of the load. The links 24 may have, if desired, a slight longitudinal swing—that is, a swing in the direction of the length of the semi-elliptic springs—so as to provide sufficient longitudinal flexibility between the 25 bolster and the semi-elliptic springs to permit the bolster to engage the transoms, and thereby relieve the springs 19 of any undue strain due to the movement of the truck when being propelled or the converse movement of 30 the bolster should the truck be employed under a car which is drawn. The connection of the cross-bars 28 with the links 24 may be rounded to allow for this play.

Instead of employing the form of spring-plank construction shown in Figs. 1, 2, 3 I 35 may employ that shown in Figs. 4, 4^a, in which the spring-plank consists of a T-iron 31, with the flange 32 vertically disposed and seated in a V-shaped cross-bar 33, having enlarged 40 heads 34 at the ends of the arms 35, which receive the ends of the links 23, the vertical flange 32 of the T-iron resting in the slot 36 of the bar and the horizontal web within a recess 37, formed upon arms, the parts being 45 connected together by bolts, as desired.

My invention also embraces the form in which semi-elliptic springs 19 rest upon other and preferably spiral springs 38, the lower ends of the spiral springs being received in 50 cups 39, resting upon the lugs 40, extending from the inner arms 5 of the axle-box pedestals, the ends of the semi-elliptic springs resting upon restraining-caps 41, which in turn rest upon the spiral springs, the latter affording by their flexibility sufficient side motion to permit the semi-elliptic springs to elongate when in use, the ends of the semi-elliptic springs resting upon the caps. The bolster 42, of any desired form, is supported upon 55 the semi-elliptic springs, so as to allow a transverse swing thereof without involving these springs, by means of the links 43, which are seated upon the recessed plate 44, secured on top of the band 45 of the semi-elliptic springs, 60 the links resting in the grooved recesses terminating in the bibs 46, which keep the links in place, and upon the lower portions of the

links rests a casting 47, likewise recessed and bibbed, which in turn supports the ends 48 of the bolster, which passes between the links 70 and under the springs, as shown in Fig. 6, the flange 49 of the casting being secured to the bolster ends. In this construction the springs 22, illustrated in connection with the preceding embodiment of my invention as being interposed between the bolster and the spring-plank, are eliminated, and the bolster rests upon and substantially ties the semi-elliptic springs together. The spiral springs 80 38 at the ends of the semi-elliptic springs resiliently support them, and by the difference in rhythm between the semi-elliptic springs and the spiral springs at their ends entirely absorb the jars and other undesirable effects of spring action and more perfectly equalize 85 the load of the car while in action or during the application of the brakes to the truck, at the same time permitting perfect flexibility between the bolster and transom and the semi-elliptic springs. 90

In the embodiment of my invention illustrated in Figs. 7, 8 I may employ either of the bolster constructions and supports therefor on the semi-elliptic springs, as previously described. However, I prefer that in this construction, for reasons which will be apparent hereinafter, the bolster 50, with the usual side and center bearings 51 52, be secured directly and rigidly to the semi-elliptic springs and that no intermediate bolster-springs be 100 employed. This may be done, as indicated, by the bolts 53 passing around the springs adjacent the band 54 and bolted to the ends 55 of the bolster. In this construction the inner arms 5 of the axle-box pedestals are 105 provided with inwardly-extending lugs 56, having a double aperture, the upper one, 57, to receive the hemispherical head 58 of a supporting-link 59, the lower aperture being larger and outwardly flared to allow the stem 110 60 of the link to play either transversely or longitudinally, the end of the link being provided with an eye 61 to receive the ends of the semi-elliptic springs 19, to which is secured the pin 62, passing through the eye, the 115 connection being pivotal with relation to the eye. The semielliptic spring being connected by the bolster, the latter is thereby free to swing transversely or longitudinally and to flatten upon the link-support. This latter being located nearer the centers of the axles, as is the support of the ends of the springs 19 in all the other forms, reduces the leverage 120 of the truck-frame in rising due to the application of the brakes or from jolts or jars incidental to the riding of the truck. To make the connection between the semi-elliptic springs and the links more flexible, the pin 125 62 may take the form of a seat 63, having a top recess 64, which receives a rounded lug 130 65, formed on the bottom of a guide-plate 66, having a groove 67, in which the ends of the semi-elliptic springs are located and which may permit the said ends to move, or the ends

of the springs may be secured directly to this seat by a pin 68, which latter should preferably be a pivotal connection. The seat is provided with rounded lugs 69, which may 5 pivotally engage the eye 61, as does the pin 62.

In Figs. 9, 10 is illustrated a further modification of the link-support. In this construction the lugs 70 support spiral springs 71, on the top of which rests a cap 72, having 10 an aperture 73 through its center and grooves 74 in its top extending from said aperture. In these grooves is seated a longitudinally-disposed pin 75. This pin pivotally supports a two-part bolt, through the eye 75^a of which 15 the pin passes, the upper part 76 of which passes through the aperture 73 in the cap 72 and an aperture 76^a in the lug, which latter should be sufficiently large to allow of the free swing of the links either longitudinally 20 or transversely, the lower end 77 of the link being provided with an eye 78, supporting a pin 79, the pin supporting the upper part of a stirrup 80, having eyes 81, through which passes a pin 82, and to this latter pin is secured 25 the ends of the semi-elliptic springs 19.

The intermediate joint of the link permits the springs on both sides of the truck and the bolster to remain in a horizontal position without bringing any lateral or torsional 30 strains on the semi-elliptic springs when the latter swing, the lateral swing of the semi-elliptic springs and bolster being had bodily from the top of the springs 71, while flexure of the spring 71 permits of sufficient longitudinal swing—that is, the link can swing bodily 35 upon the pin transversely, while longitudinal swing may be provided for by the flexure of the upper portion of the spiral springs.

The result of the construction shown in 40 Figs. 1, 2, 3, and 4 is that the springs coöperate together, so that vibrations of the car-body are first taken by the elliptic bolster-springs and then transmitted horizontally to the semi-elliptic equalizer-springs and thence 45 vertically to the spiral axle-box springs, so that all act together in breaking up the primary rhythm of each kind of spring and produce a maximum effect to reduce the said vibrations and at the same time efficiently support 50 the car-body. In the other modifications herein shown and described a similar effect is produced in a different way.

From the foregoing it will be clear that the support of the semi-elliptic springs from the 55 axle-box pedestals can be accomplished in a variety of ways in accordance with my invention and considerably modified without departing from the spirit thereof.

Having described my invention, I claim—

60 1. The combination in a truck having side frames with top chords and axle-box pedestals with projections extending from said pedestals below said chords, longitudinally-disposed semi-elliptic springs with ends adapted 65 to longitudinally slide upon and to extend above said projections, and a bolster support

ed by and transversely connecting said semi-elliptic springs below the top chords.

2. The combination in a truck having a frame and axle-box pedestals, the longitudinally-disposed semi-elliptic springs movably supported upon the inner arms of the axle-box pedestals, and a bolster supported by said springs and adapted to swing therefrom. 70

3. The combination in a truck having a frame, and axle-box pedestals provided with inwardly-extending lugs, upwardly-arched and semi-elliptic springs supported by said lugs, and a bolster extending between and adapted to swing from the arches of said semi-80 elliptic springs. 85

4. The combination in a truck, having a frame comprising a top bar and connected axle-box pedestals, lugs extending inwardly from the axle-box pedestals, longitudinally-disposed semi-elliptic springs under said top bar and having their ends supported by said lugs, and a bolster extending between the transoms, its ends being supported on the said springs. 90

5. The combination in a truck having a frame and axle-box pedestals provided with inwardly-extending lugs, longitudinally-disposed and upwardly-arched semi-elliptic springs supported by said lugs, swing-links 95 supported on the semi-elliptic springs, and a bolster pivotally supported by said links.

6. The combination in a truck having a frame and axle-box pedestals provided with inwardly-extending lugs, upwardly-arched 100 semi-elliptic springs supported by said lugs, links resting upon the semi-elliptic springs, and adapted to have longitudinal and transverse swing, and a bolster pivotally supported by said links. 105

7. The combination in a truck having a frame and axle-box pedestals provided with inwardly-extending lugs, the longitudinally-disposed and upwardly-arched semi-elliptic springs supported by said lugs, a spring-plank 110 supported by said semi-elliptic springs, further springs supported on said plank, and a bolster supported on said latter springs.

8. The combination in a truck having a frame, and axle-box pedestals provided with inwardly-extending lugs, upwardly-arched semi-elliptic springs supported by said lugs, links supported by said semi-elliptic springs, a spring-plank movably supported by said links, springs on said plank, and a bolster 120 supported on said latter springs. 115

9. In a car-truck, the combination with a frame and the longitudinally-disposed semi-elliptic springs, a cap or cross-bar supported by said semi-elliptic springs, links pivotally supported at the ends of said cross-bar and embracing said springs, a cross-bar resting upon the lower ends of said links, and means for supporting a bolster on said latter cross-bar. 125

10. The combination in a truck, of the truck-frame, and the longitudinally-disposed

semi-elliptic springs, a cap or cross-bar supported on said semi-elliptic springs, links depending from said cross-bar, a cross-bar connecting the lower ends of said links below 5 said springs, a spring-plank supported on the latter cross-bar below said springs, springs on the spring-plank, and a bolster supported on said latter springs.

11. The combination in a truck, of the 10 truck-frame, the longitudinally-disposed semi-elliptic springs, links supported from the semi-elliptic springs, a T-iron cross-bar located below said semi-elliptic springs, recessed cross-bars receiving the T-iron cross-bars, the T-shaped cross-bars being supported by said 15 links, and a bolster supported upon said T-iron cross-bar.

12. In a car-truck, the combination with the truck-frame, semi-elliptic springs supported by the truck-frame, link-blocks supported on the top of the semi-elliptic springs, links supported by said link-blocks, a cross-bar resting upon the bottom of said links and pivotally supported thereon, and a bolster, 25 supported by said cross-bar.

13. In a car-truck, a frame, a bolster, a spring-plank, springs interposed between the bolster and spring-plank, semi-elliptic springs supporting said spring-plank, and resilient 30 means for supporting said semi-elliptic springs.

14. In a car-truck, the combination of a 35 frame, spiral and semi-elliptic springs in the same vertical plane, elliptic springs in transverse alinement with said semi-elliptic springs and a bolster supported by said elliptic springs.

15. In a car-truck, the combination of a frame, spiral and semi-elliptic springs in the same vertical plane, further springs in transverse alinement with said semi-elliptic 40 springs, and means for sustaining said springs in the proper positions relative to the frame.

16. In a car-truck, the combination with the 45 spring-supported side frames, the longitudinal semi-elliptic springs supported by the side frames, a spring-plank supported on the semi-elliptic springs, elliptic springs on said plank, and a bolster on the latter springs.

17. In a car-truck, the combination with 50 the spring-supported side frames, the longitudinal semi-elliptic springs supported by the side frames, a transverse spring-plank, links pendent from the tops of the semi-elliptic springs and supporting said plank, longitudinal 55 elliptic springs on said plank, and a bolster on said latter springs.

18. In a car-truck, the combination with the side frames having spring-supported axle-box pedestals, longitudinal semi-elliptic 60 springs supported by the projections below the top of the side frames, links pendent from the semi-elliptic springs, a lateral spring-plank supported by said links, longitudinal 65 elliptic springs on said plank, and a bolster on the latter springs.

Signed in the city and county of Philadelphia, State of Pennsylvania, this 18th day of June, 1902.

WALTER S. ADAMS.
